(57) **CLAIM**

The ornamental design for a snow paddle, as shown and described.

DESCRIPTION

FIG. 1 is a perspective view for a snow paddle showing our new design in a fully extended position;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a perspective view for a snow paddle showing our new design in a fully closed position;

FIG. 9 is a top plan view thereof;

FIG. 10 is a bottom plan view thereof;

FIG. 11 is a right side elevation view thereof;

FIG. 12 is a left side elevation view thereof;

FIG. 13 is a front elevation view thereof; and,

FIG. 14 is a rear elevation view thereof.

A portion of the disclosure of this patent document contains material which is subject to trademark and copyright protection. This patent document shows a copyrighted and trade dress logo for Snoshark which is owned by Stephen and Lorraine Wood. The copyright and trade dress owners have no objection to the facsimile reproduction by anyone of the patent disclosure as it appears in the Patent and Trademark Office patent files or records, but otherwise reserve all copyright and trade dress rights whatsoever.

The broken lines in the figures represent features of the Snow Paddle that form no part of the claimed design.
